UNITED STATES PATENT OFFICE.

ISAAC E. PALMER, OF MIDDLETOWN, CONNECTICUT.

DESIGN FOR FABRIC.

SPECIFICATION forming part of Design No. 31,111, dated June 27, 1899.

Application filed May 22, 1899. Serial No. 717,854. Term of patent 14 years.

To all whom it may concern:

Be it known that I, ISAAC E. PALMER, a citizen of the United States, and a resident of Middletown, in the county of Middlesex and State of Connecticut, have invented and produced a new and original Design for Fabrics, of which the following is a specification, reference being had to the accompanying drawings, forming a part thereof.

5 The leading feature of my design consists in a fabric in which the threads extend in groups in one direction along the fabric, each group being composed of three threads, the two outer of the three threads crossing each other at intervals and the central thread of the three extending along a central line between the said outer threads, the said groups of three threads each being intercepted by a series of single threads extending in the opposite direction across the fabric and crossing the groups at the points where the outside threads of each group cross each other and also at points intermediate of these crossing points, the said cross-threads extending between the central threads of each group and

the two outside threads. When viewed from the opposite side, the central thread of each group of three appears at intervals only between the outside threads at points intermediate of their crossing-points.

In the accompanying drawings, Figure 1 represents a portion of the fabric when viewed from one side, and Fig. 2 represents the same when viewed from the opposite side.

The several groups of three threads are denoted by A, the central thread of each group by a , and the opposite threads of each group by a' a'' . The threads which run in the opposite direction are denoted by B.

What I claim is—

The design for a fabric, substantially as herein shown and described.

In testimony that I claim the foregoing as my invention I have signed my name, in presence of two witnesses, this 19th day of May, 45 1899.

ISAAC E. PALMER.

Witnesses:

E. B. WETMORE,
P. S. CARRIER.
